WALL BLOCK

Arthur Q. Davis, 2475 Canal St., New Orleans, La.

Filed Aug. 23, 1960, Ser. No. 61,861

Term of patent 14 years

(Cl. D18—2)

Fig. 1.

Fig. 2

Fig. 3

Fig. 4.

I claim:

The ornamental design for a wall block, as shown and described.
